COMBINATION PULLER

Application filed February 2, 1932. Serial No. 590,476.

This invention relates to a combination pulling device and aims to provide an improved combination puller to facilitate the dislodgment or unseating and removal of 5 various articles from their supporting structures.

A device of this character is particularly useful as an aid in the removal of bearings, washers, gearing, etc. from shafting or from 10 the interior of tubular members, for the withdrawal of automotive rear axle shafts, and for other like purposes.

For the removal of articles of this character is particularly desirable that provision be 15 made for so positioning the tool that the pulling stress will be symmetrically applied to the article to be moved. For example, in the removal of hardened members from stud shafting, it is particularly necessary that the dis- 20 lodging force be applied symmetrically about the member and in a direction to pull it smoothly along the shaft, as any unbalance of the applied force will tend to pull one side of the member more rapidly than the other 25 and cause it to dig into the shaft with consequent increase of the force necessary to remove it, and possible warping or scoring of the shaft itself to an extent which might impair its running in journal bearings, or the 30 application of further cooperative members thereto.

In addition we have found that in the removal of articles from stud shafting or the like, the dislodgment of the article is greatly facilitated by applying to the article an initial stress tending to urge it in the direction in which it is to be moved, which stress is maintained up to and through the moment of applying a dislodging shock in the same direction. By this novel provision the cumulative effect of the initial stress and the dislodging shock is made available to dislodge articles which could not be readily dislodged by the shock alone.

Furthermore, in the pulling of shafting, bearing caps or other articles which should be pulled in a direct line to prevent distortion of the articles themselves or of members positioned adjacent thereto, and to enable their 50 removal with the least possible effort, it is

desirable that provision be made for insuring aligned application of the removing force, and our invention is particularly adapted to this end.

Other objects and advantages of our invention will be readily apparent from the following description of a preferred form of combination puller and accessories embodying the same; and in the accompanying drawings showing such preferred embodiment for the purposes of illustrating our invention:

Fig. 1 is an assembly view of a puller provided with three arm means for engaging an article;

Fig. 2 is a detail view of the arm receiving cross member of Fig. 1;

Fig. 3 is a similar assembly view with parts in section of a puller provided with two arm article engaging means and spreader means therefor;

Figs. 4 and 5 are elevation and plan views, respectively, of a hub pulling attachment, Fig. 4 being partially sectioned on the line 4-4 of Fig. 5; and

Figs. 6 and 7 are detail views of further accessories to the tool.

In the particular embodiment of our invention selected for illustration herein and shown in the drawings, referring particularly to Figs. 1 and 2, the combination puller comprises a rod 10 threaded for a substantial distance at its inner end and provided with a head 11 shaped to receive turning means such as a wrench and/or turning bar for the purposes hereinafter described. This head 11 may be formed integrally with rod 10 or secured thereto in any desired way, a satisfactory and economical manner of construction being indicated in Fig. 3, which shows the head 11 threaded to rod 10 and fastened in place thereon by a driven pin 12 passing through the head and rod and filed flush with the exterior surface of the head. This figure of the drawings also shows an aperture 13 extending into or through the head 11 to provide for the application of a turning rod or lever thereto, as above described, to set up the rod during use of the device.

The rod 10 carries on its shaft a sliding weight or hammer member 14 adapted to be

firmly knocked against its head 11 to apply pulling shock to the rod, and is adapted to be screwed through a suitable cross member 15, 15a which is preferably provided with bifurcated ends to receive the article engaging arms 16, which may be of any desired number, but are preferably symmetrically arranged about the rod. The arms are secured to the cross member in any suitable fashion, 10 the securing means shown comprising headed pins 17 retained by cotter-pins 18, which are easily removed to permit reversal of the arms 13 to direct their hooked article engaging ends either inwardly or outwardly (see Figs. 1 and 3), or to permit the substitution of other types of arms or engaging means therefor, as hereinafter described. The hooked ends of the arms may be shaped, if this is desired, to form an angle of less than 90° with respect to the direction of pull to provide an article engaging means which will obtain a firm purchase on the article to be pulled, and assist in holding the tool in preliminary attached position as hereinafter described. 20

25. It will be noted that in the forms shown the bifurcations of the cross member 15, 15a providing for attachment of the article engaging arms 16, are symmetrically located on opposite sides of the rod 10 to provide for 30 equal distribution to the arms 16 of any force applied through the rod 10, so long as the rod 10 is aligned in the direction in which the article is to be pulled. As above mentioned this provision is particularly necessary in delicate removal operations where care must be taken not to deform the article being dislodged or any delicate surrounding parts.

35. The means to insure the alignment of the rod 10 with the direction in which the force is to be applied, in the embodiment shown, is provided by the threaded portion of the rod 10 which enables the rod to be extended between the article engaging arms 16, or members substituted therefor, and into engagement with the end of the shaft from which the article is to be pulled, or with a portion of the article itself. By this means, and with the assistance of the hooked ends of the article engaging members, particularly if these ends be shaped to be self-gripping as above mentioned, the entire puller may be rigidly attached in operative engagement with the article to be pulled, with its rod 10 aligned 40 in the direction in which the pulling force should be applied.

45. This arrangement is also particularly desirable in enabling the application of initial tension to the article to be pulled. For example, in pulling a gear from a shaft, the rod 10 may be screwed down tightly against the end of the shaft by means of a wrench applied to the head 11; thus applying a substantial tension to the arms 16 engaged with 50 the gear or like element which is to be re-

70 moved from the shaft. By this arrangement aligned initial tension is maintained up to and during the moment of the application of pulling shock by the sudden knocking of the hammer member 14 against the head 11.

75 In the preferred embodiments of our invention shown in the drawings, to facilitate alignment and avoid distortion of the rod 10 when screwed tightly into engagement with an abutment for aligning the tool with, and/or applying initial tension to, an article to be pulled, we provide the engaging end of the rod 10 with a hardened relatively pointed bearing-tip 19 (see Figs. 1 and 3) to avoid 80 tendency of the rod to "meander" as results if a flat end is rotated against a surface, and this relatively pointed tip is adapted particularly for cooperation with the center-holes formed at the centers of the ends of most machined shafting, axles, and other stock during the manufacture of the same, to provide exact alignment of the tool therewith.

85 Furthermore, in situations where the operator is cramped for space, the extensibility of the rod 10 is particularly advantageous even where its aligning and tension applying utilities are not employed, as by this arrangement the length of the rod 10 can be adjusted to the greatest length allowed by the space available, so that a maximum throw of the hammer can be obtained; and as the article is gradually withdrawn, the rod can be 90 screwed in to maintain clearance between the head of the rod and any interfering structure which would otherwise be abutted there-by before substantial or complete removal of the article.

95 Thus in the removal of an internal washer bearing, such as a grease retainer in the rear axle housing of an automobile, when, as is frequently the case, the space between the end of the housing and the garage wall or other obstruction is cramped, the rod 10 can be 100 screwed through the cross member 15, 15a into the interior of the housing, as the grease retainer is withdrawn, to maintain the head 11 clear of the interfering garage wall or other structure.

105 In pulling of this character, when using the equipment so far described in a manner to enable free running of the rod 10 through the member 15, 15a, the hooked ends of the arms 16 may be maintained in engaged relation with the article being pulled by grasping the rod 10 adjacent its threaded portion and thus holding the hooked ends tightly against the article, and in this connection a self-gripping construction of the hooked ends of the rods, mentioned above, is of particular utility.

110 A further cooperating feature of our invention, of particular utility in pulling operations where the aligning or tension applying functions of the rod 10 need not be 115

used but where it is difficult to obtain and maintain the engagement of the arms 16 or similar movable members with the article to be pulled, resides in the provision of engagement setting means comprising members 20, 20^a (Fig. 3) adapted to be carried by the rod 10 and be manipulated by adjustment of the rod to effect and maintain the engagement of such movable work engaging members. In 10 the form shown the engagement setting members 20, 20^a are formed to cooperate with the inner faces of the inwardly inclined portions of the bent arms 16 so that movement of the setting member longitudinally between the 15 arms will effect outward displacement thereof to cause and maintain engagement of the hooked ends of the arms with the work. In the preferred embodiment of our invention illustrated in the drawings the setting member 20, 20^a is in the form of a disc having its 20 peripheral portion shaped to smoothly slide between the inner faces of the arms 16 and provided with a central aperture to engage over the end of the rod 10 in mounting the 25 setting member thereon, means being provided to retain the setting member at a predetermined position on the rod, which comprises any suitable stop means such as the shoulder 22 (Fig. 1) provided by reducing 30 the end of the rod at 23 to a diameter less than that of the threaded portion thereof. By making the member setting means readily demountable, as shown, and confining all 35 portions of the end of the rod 10 to a diameter less than that of the threaded portion thereof, provision is also made for ready removal of the cross member 15, 15^a to enable the use of substitute cross-members of different proportions or the use of accessory articles 40 engaging means such as that shown in Figs. 4 and 5 and hereinafter described.

By positioning the arms of our puller so that their hooked ends are turned inwardly as shown in Fig. 1, the device is adapted for 45 use for work such as the pulling of an axle shaft from its housing, in which case a nut will be threaded onto the end of the axle, the hooked arms will be placed behind the nut, and the rod 10 will be screwed down 50 into engagement with the end of the axle shaft to position the rod 10 in direct alignment with the axle. The puller being thus rigidly attached to the axle, the sliding weight 14 may be manipulated against the 55 head 11 to apply pulling shock to the axle shaft, and thus withdraw it from its assembled position by a direct lineal pull. This avoids any danger of bending the axle or any grease retainers, rings, or bearing races 60 associated therewith, and prevents injury to its threaded end; all of which difficulties are likely to be experienced in removing an axle in the usual way by the application of a sledge or other hammer obliquely on the nut 65 carried by its end.

Furthermore, the bifurcated construction of the ends of the cross member 15, 15^a enable the insertion therethrough, in lieu of the arms 16, of studs or other screw members, and this provision is particularly advantageous 70 in the removal of wicked or similar bearing caps and like parts. In such cases the studs may be threaded into the bearing caps, and the rod 10 may be screwed tightly down against the same to hold the bifurcations of the member 15, 15^a tightly engaged 75 with the heads of the studs and hold the rod 10 aligned with the direction of pull; after which the hammer 14 may be manipulated to dislodge the bearing cap or like part. A sufficient shock can be obtained to cut the wicking or other elements interfering with 80 dislodgment of the cap, thus obviating the difficulties heretofore experienced in removing the same before the cap could be withdrawn. 85

To further extend the range of usefulness and/or convenience of application of our device to various sorts of pulling operations, further supplemental or substitute accessory 90 parts may be employed in conjunction with the combined anvil headed hammer carrying and adjustable rod 10 which provides either pulling, aligning, tension applying, tool setting, and/or other cooperating function in 95 our impact tool, and Figs. 4 through 7 are illustrative of such further accessory parts.

The accessory shown in Figs. 4 and 5, for example, comprises a thimble body 30 provided with an end aperture 31 threaded to 100 engage with the rod 10 to enable the thimble to be substituted for the cross-member and arm assemblies of Figs. 1 and 2. At its open face the thimble is provided with one or more series of uniformly spaced stud receiving apertures 32, 33 adapted to cooperate with the wheel retaining studs carried by hubs provided with demountable wheels for securing the thimbles to such studs. The thimble is also provided with means such as the hexagonal shaped portion 34 to enable the thimble and hub to be held stationary during rotation of the tension applying rod 10, or vice versa, to enable the application of a high initial tension to assist in removing the hub. 110 One or more apertures 35 may be provided in the sides of the thimble to enable inspection of the abutment of the puller rod 10 with the end of the axle, etc., and, as our invention contemplates the application of a nut to the 120 axle-shaft in spaced relation to the hub to be pulled to prevent the hub being jerked entirely off the axle by the sudden heavy impact provided by the heavy embodiments of our tool utilized in this connection, the apertures are of additional utility to enable adjustment of such stop-nut, which is indicated at 36 in Fig. 4.

The accessory shown in Fig. 6 comprises a yoke or washer 40 intended for use with a 130

pair of bolts and nuts of a size to fit the bifurcations of the cross-member 15^a (Fig. 3), and having apertures 41 correspondingly sized. This yoke member is intended to be dropped down over the narrow neck of the style of undemountable automobile wheel or the style of hub for a demountable wheel having such narrow-neck behind its hub-cap carrying portion, after which the bolts and nuts, which are inserted in the holes 41 are of such length as to extend outwardly beyond the end of the axle from which the wheel is to be pulled, are engaged in the bifurcated portions of the cross-member 15^a (Fig. 3). The wheel retaining axle nut and associated parts having been removed, the rod 10 may now be screwed through the cross-member 15^a to apply initial pulling tension to the wheel, which may then be augmented by the sudden hammer impact to effect quick removal thereof. As described in connection with the thimble shown in Figs. 4 and 5, a nut may be applied to the axle in spaced relation to the unit to be pulled to prevent its being jerked entirely off the axle.

A similar device is shown in Fig. 7, this being a threaded nut adapted to be used in the pulling of wheels fairly easily removed and provided with exteriorly threaded hubs. This device comprises a nut member 50 provided with a "mongol" threaded aperture of the diameter of the hub of the wheel to be pulled. The "mongol" thread enables the nut to fit any usual thread of whatever type, found upon members of a diameter corresponding to that of the aperture. This nut is provided with two bifurcated extensions 51 in the embodiment shown, adapted to receive members to connect the nut to the bifurcated portions of the cross-member 15^a (Fig. 3). Upon such assembly of the parts the rod 10 may be run into tensioning position and the wheel pulled either with or without the use of a pull-off stop-nut applied to the axle as above described.

It is obvious from the foregoing description that the combination device provided by our invention is particularly flexible in its application and may be employed in the removal of almost any type of article which can be reached by the arms 16 or any other type of arms or engaging means which may be provided with the tool or constructed on the spot to fit the particular job to be done. The arms provided with the tool may even have malleable shanks enabling them to be bent into different forms in order to reach articles difficult to remove because of interfering structure, and it is clear from the foregoing description that our device may be employed for a large variety of special jobs in addition to the general run of work, in which a pulling operation is required, by the provision of accessory parts to adapt it for such special purposes. While it is pref-

erable to provide the device with means for engaging the article to be pulled, symmetrically arranged about the rod 10, as in Figs. 1, 3, 4, 5 and 7 herein, it is clear from the foregoing description that unsymmetrically arranged engaging means may be associated with our combination puller to adapt it for operations which require such means for their performance.

It is thus clear that our invention may be embodied in other specific forms without departing from the essential attributes thereof, and we therefore desire the present detailed description to be considered in all respects as illustrative and not restrictive.

We claim as our invention:

1. An article pulling tool comprising a rod threaded for a substantial part of its length, a head on said rod adapted to receive a wrench, a cross bar through which said rod is adapted to be screwed, article engaging arms pivotally and reversibly secured to said cross bar, said threaded rod being adapted to be screwed down into engagement with a surface with respect to which the article is to be pulled to exert an initial tension on said article and hold the tool in axial alignment with the direction of pull, and a weight slidably mounted on said rod and adapted to be manipulated against said head with sudden force to augment said initial tension at the moment of impact, and thereby exert a cumulative stress to cause movement of said article.

2. A combination puller comprising a puller rod provided with a head at one end and an extended threaded area at the other end, and having a slideable hammer mounted thereon, a cross member carried by said rod provided at points symmetrically related thereto with means for symmetrically engaging an article to be pulled, said extended threaded area providing for movement of said rod through said member to move its end into engagement with an abutment associated with the article to be pulled to hold said pulling rod in proper alignment therewith; whereby impact of said hammer with said head is transmitted symmetrically and in proper alignment to the article to be pulled.

3. A combination puller comprising a rod having an extended threaded area at one end and provided at its other end with a wrench receiving head; a member through which said rod is adjustably threaded to enable it to be set up therethrough; said member being formed to receive, in symmetrical relation to said rod, means for securing the puller to the article to be moved; and means slideable on said rod to impact said head for applying a sudden pulling shock to said rod.

4. A combination tool of the class described comprising article engaging arms, a connecting bar to which said arms are pivoted in symmetrical relation to its center, a

- rod longitudinally adjustable through said center of said connecting bar, a head on said rod adapted to receive a wrench for setting up said rod in use of the device, and a member 5 slidable on said rod against said head with a hammer effect to apply a sudden shock longitudinally of said rod for symmetrical distribution by said arms to the article engaged thereby.
- 10 5. A combination puller comprising article engaging arms having hooked ends formed to maintain engagement with the article to be pulled, a connecting bar on which said arms are pivotally and reversibly mounted, a rod threaded through said bar and adapted to engage against a surface to hold said puller in alignment with the direction in which the article is to be pulled and with its arms engaged with the article, 15 a head on said rod providing means facilitating the turning of said rod into such surface engaging position, and a weight slidable mounted on said rod and adapted to forcibly engage said head to exert a sudden, 20 properly aligned pulling shock on the article to be moved.
6. A combination puller comprising a rod threaded throughout a substantial portion of its length, a hammer slidable on said rod, 25 a head carried by said rod to be impacted by said hammer, and means adapted to engage an article to be pulled and provided with a threaded aperture extending in the direction of pull and formed for adjustable engagement with the threaded portion of said rod to provide for setting up said rod against an abutment in use of the device as a preliminary to manipulation of said hammer.
7. A combination puller comprising a rod 30 threaded throughout a substantial portion of its length, a hammer slidable on said rod, a head carried by said rod to be impacted by said hammer, and means adapted to engage an article to be pulled and provided with a threaded aperture extending in the direction of pull and formed for adjustable engagement with the threaded portion of said rod to provide for setting up said rod against an abutment in use of the device as a preliminary to manipulation of said hammer, the 35 abutment engaging end of said rod being provided with a contacting end of reduced area to avoid "meandering" of said end during setting up of the same against said abutment.
8. A combination puller comprising a rod 40 threaded throughout a substantial portion of its length, a hammer slidable on said rod, a head carried by said rod to be impacted by said hammer, and means adapted to be secured to a wheel-hub to be pulled and provided with a threaded aperture positioned to align with the axle from which the hub is to be pulled and formed for adjustable engagement with the threaded portion of said rod, whereby initial pulling stress may be applied by adjustment of said threaded rod and augmented by dislodging blows of said hammer on said head, and a stop nut adapted to be secured on said axle in spaced relation to the hub to be pulled therefrom to prevent jerking of the hub entirely from the axle.
11. A combination puller comprising a rod 45 threaded throughout a substantial portion of its length, a hammer slidable on said rod, a head carried by said rod to be impacted by said hammer, and a thimble adapted to be secured to a wheel-hub to be pulled and provided with a threaded aperture positioned to align with the axle from which the hub is to be pulled and formed for adjustable engagement with the threaded portion of said rod, whereby initial pulling stress may be applied by adjustment of said threaded rod and augmented by dislodging blows of said hammer on said head, and a stop nut adapted to be secured on said axle in spaced relation to the hub to be pulled therefrom to prevent jerking of the hub entirely from the axle, 50 said thimble being formed to provide for access to said stop nut.
12. A combination puller comprising article engaging arms having hooked ends formed to maintain engagement with the article to be pulled, a connecting bar on which said arms are pivotally and reversibly mounted, a rod threaded through said bar and adapted to engage against a surface to hold said puller in alignment with the direction in which the article is to be pulled and with its arms engaged with the article, a head on said rod providing means facilitating the turning of said rod into such surface engaging position, a 55

weight slidably mounted on said rod and adapted to forcibly engage said head to exert a sudden, properly aligned pulling shock on the article to be moved; said arms 5 being shaped to present normally inclined cam surfaces between their ends and their points of connection to said connecting bar, and a cam member removably mountable on said rod and when mounted thereon cooperative with said cam surfaces to pivot said arms into article engaging position when advanced by threading of said rod through said connecting bar, said cam surfaces and removable cam-member thus providing for 10 converting the tool to facilitate its employment with work presenting no surface engageable by said rod as aforesaid.

13. A combination puller according to claim 12 in which said rod is provided with 20 an end projection of reduced cross-section and presents a shoulder at the juncture of said projection and the threaded portion of the rod, and in which said cam-member is provided with an aperture of a size to slidably fit said end projection, whereby the removable mounting of said cam member on said rod may be effected by placing it over said end projection and into engagement with said shoulder, said cam surfaces being so inclined that said arms are pivoted into article 25 engaging position by pushing of said cam member away from said connecting bar by said rod, whereby said loosely mounted cam-member will not become disengaged from said end projection in use of the tool with said cam member mounted as aforesaid.

In testimony whereof, we have signed our names to this specification.

40 PHILLIPS H. CLARKE.
